SIGN FRAME

Howard T. Hallowell and Frank Bennett, Jenkintown, Pa., assignors to Standard Pressed Steel Co., Jenkintown, Pa., a corporation of Pennsylvania

Application June 30, 1932. Serial No. 620,203

3 Claims. (Cl. 40—125)

One object of our invention is to so construct a sign frame that the sign can be readily placed in position or readily removed therefrom for the insertion of another sign.

5 Another object of the invention is to so construct the sign frame that the sign can be removed from the top of the frame, the top being capable of being moved to one side of the frame to allow for the ready insertion or removal of the 10 sign.

In the accompanying drawings:

Fig. 1 is a perspective view of our improved sign frame mounted on a pedestal;

Fig. 2 is a side view of the upper portion of the 15 frame;

Fig. 3 is an end view of the upper portion of the frame with the movable top member in position;

Fig. 4 is a view similar to Fig. 3 with the top 20 member turned to one side to allow for the insertion of a sign;

Fig. 5 is an enlarged side view partly in section of one of the upper corners of the frame;

Fig. 6 is a sectional view on the line 6—6, Fig. 5; 25 Fig. 7 is a sectional view on the line 7—7, Fig. 5;

Fig. 8 is a detached perspective view of the movable top member of the sign;

Fig. 9 is a perspective view of our improved sign showing the transverse partitions located in 30 the frame and also showing the sign frame mounted on feet;

Fig. 10 is a perspective view illustrating another form of the frame mounted on legs and showing a modification of the transverse partitions;

Fig. 11 is a detached sectional view of the top member.

Referring in the first instance to Figs. 1 to 8, inclusive, 1 is a rectangular sign frame. The 40 side members 2—2 are made of channel bars such as shown in Fig. 7, having portions 3 which are bent inwards to form guides for the sign. The bottom members 4 consist of two members spaced apart for the insertion of the sign, and in the 45 present instance the sign is mounted on a pedestal 5 having a base 5a, the upper portion of the pedestal extending between the two bars 4—4 and welded or riveted thereto, but it will be understood that the sign may be mounted on legs

50 such as illustrated in Figs. 9 or 10 without departing from the essential features of the invention. The upper end of the frame is open for the insertion of a sign and can be closed by a movable top member 7. The two side members being spaced apart and disconnected at the upper

end except by the movable top member, which acts to hold the two side members in alignment at all times whether the top member is in one position or the other. This member is shaped in cross-section as shown in Fig. 6, and the portions 8 are bent outwards as shown in the present instance so as to overlap the side members of the sign frame when moved into position to shed water. At each end of the member 7 in the present instance are angle pieces 10, which have 60 portions 11 welded to the body 12 of the top member and have portions 13 which extend down and fit against the side members 2 of the frame and hold the said side members of the frame in alignment, as clearly shown in the drawings. 65 Each of these portions 13 are slotted as at 14 and headed pins 15 extend through the slots and are riveted to the side members as clearly shown in Fig. 5. The slot is of sufficient length that when the top member is raised to a given height 70 according to the length of the slot, it can be turned from the position shown in Fig. 3 to the position shown in Fig. 4, leaving the top of the frame open to allow for the insertion or withdrawal of a sign, the side members being held 75 in alignment by the top member when the top member is turned back. When the sign is in position, the top member is turned back to the vertical position and will drop onto the side members of the frame, the side members holding 80 the top member in position. In the present instance the flanges 16 of the angle pieces 10 extend on each side of the side members when the top member is in position, but they are cut away 85 so as to allow the top member to swing freely 90 when the said member is raised to its fullest extent. In some instances, the top member 7a may be formed in a single piece of metal as shown in Fig. 11, the ends 13a being extensions of the body 95 portion.

Fig. 9 illustrates the frame constructed as shown in Fig. 1, with the exception that the frame is mounted on legs 17 secured by brackets 18 to each of the side frames in place of the pedestal shown in Fig. 1, and in this instance we have illustrated transverse partition bars 19, which extend from one side frame to the other and are used to separate short series of small signs when necessary. 105

In Fig. 10 we have illustrated a modification of the side members of the frame. The legs 17a in this instance are secured to the outside of the frame. It will be understood that either of the frames shown in Figs. 1, 9 and 12 may be sup- 110

ported in any suitable manner without departing from the essential features of the invention.

We claim:

1. The combination in a sign frame, of a bottom member; two channeled side members extended upwardly from the bottom member, the space between the side members being open to allow for the insertion of a sign from the top of the frame; a movable channeled top member extending from one side member to the other and having downwardly projecting slotted portions preventing the spreading apart of the side members, said slotted projections also having portions arranged to embrace the surfaces of said side members and prevent movement of the top member when the latter is lowered into position overlying the ends of the side members; and pins on the outside of the side members extending into the slots of the downwardly projecting slotted portions.
2. The combination in a sign frame, of a bottom member; two channeled side members extending upwardly from the bottom member, the space between the side members being open at the top to allow for the insertion of a sign; a movable channeled top member extending from one side member to the other; angle pieces se-

cured to each end of the top member, said channel members having downwardly projecting slotted portions fitting on the outside of each side member; and headed pins on the outside of the side members and extending into the slots in the downwardly projecting portions, the said top member with its angle pieces holding the upper portions of the side frames in alignment when the top member is in either of its two positions.

80

3. The combination in a sign frame, of a bottom member; two channeled side members extending upwardly from the bottom member, the space between the side members being open to allow for the insertion of a sign; a channeled top member having portions bent inwardly to form a contracted opening for the sign, the ends of said portions being bent outwardly so as to overlap the side members of the sign frame when the top member is above the side members, the flared portions overlapping the side members so as to shed water; slotted angle pieces secured to the ends of the top member; and pins on the outside of the side members extending through the slots in the angle portions.
